Attn.

UNITED STATES PATENT OFFICE.

JOHN SHORT, OF COLUMBUS, OHIO.

CHAIR.

SPECIFICATION forming part of Letters Patent No. 326,165, dated September 15, 1885.

Application filed July 23, 1883. (No model.)

To all whom it may concern:

Be it known that I, JOHN SHORT, of Columbus, in the county of Franklin and State of Ohio, have invented a new and useful Improvement in Chairs; and I do hereby declare that the following is a full, clear, and exact description of the same.

My invention relates to an improvement in the construction of chairs; and the object of the invention is to provide a common chair with a spring attachment which at small cost will greatly increase the comfort of the occupant of the chair and convert such chair into a kind of rocker.

15 My invention consists, mainly, in a chair provided with telescoping legs, and with a spring interposed between the chair-seat and the leg, which permits such seat to yield vertically, and, further, in details of construction 20 shown in the accompanying drawings, and hereinafter fully described and claimed.

In the said drawings, Figure 1 is a front elevation of a chair. Fig. 2 is a sectional view of one of the chair-legs.

25 A represents a chair-bottom of any preferred construction.

B B represent hollow legs or sleeves secured to the bottom, one at each corner.

30 C C are solid legs adapted to telescope within the legs B B and to slide freely therein. These are the supporting-legs proper of the chair, and rest upon the floor. The sleeves B B are slotted, as shown at b, and within these

slots work the free ends of leaf-springs a a, the centers of such springs being secured to the chair-bottom. The ends of the springs rest upon the tops of the solid legs C C, there being necessarily one of the springs for each pair of legs. The springs form a yielding support for the chair-body, and when such chair-body is depressed by the weight of the occupant the telescoping legs move in opposite directions, the ends of the spring being forced upward.

I am aware that hitherto separate spiral 45 springs have been inclosed in each hollow leg surrounding a solid leg, by which the chair-seat receives an elastic support.

For some kinds of chairs I may prefer to dispense with the leaf-springs and employ a 50 single coil-spring for each leg.

Having described my invention, I claim— Combined with a chair-seat, the hollow legs B, having the slot b, the solid legs C within the said hollow legs, and leaf-springs a, one 55 for each pair of legs, secured at the middle to the chair-bottom, and having their ends extending through the slots b and resting on the solid legs, substantially as described.

In testimony whereof I have signed my name 60 to this specification in the presence of two subscribing witnesses.

JOHN SHORT.
